UNITED STATES PATENT OFFICE.

KARL C. RANDALL, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,226,114.

Specification of Letters Patent.

Patented May 15, 1917.

Application filed April 6, 1914. Serial No. 829,861.

To all whom it may concern:

Be it known that I, KARL C. RANDALL, a citizen of the United States, and a resident of Edgewood Park, in the county of Allegheny and State of Pennsylvania, have invented a new and useful Improvement in Circuit-Interrupters, of which the following is a specification.

My invention relates to circuit interrupters, and it has, as its object, to provide auxiliary means for assisting in the operation of the same.

When circuits are interrupted under abnormal loads, a gas is developed which retarded the downward movement of the contact members in the oil in which they are immersed, by reason of the piston-like action of the operating rod. In my invention, I provide means for conducting the generated gas away from the contact members and for utilizing the same in aiding the operation of the circuit interrupter.

The single figure of the accompanying drawing is a view, partially in section and partially in elevation, of a three-phase circuit interrupter embodying my invention.

The three-phase circuit breaker shown in the drawing comprises three similar units 1, 2 and 3 severally comprising a receptacle 4, a plurality of stationary contact members 5, a plurality of movable contact members 6, an operating rod 7, condenser terminal bushings 8 and a toggle mechanism 9. The toggle mechanisms 9 are operatively connected together by a rod 10, and the toggle mechanism 9 of the unit 1 is connected by a rod 11 to one arm of a bell crank lever 12, the other arm of which is connected, by a rod 13, to one arm of a bell crank lever 14. The remaining arm of the bell crank lever 14 is connected, by a rod 15, to an operating lever 16, substantially as shown in the drawing. A tripping device 17 comprises a winding 18, a movable core member 19, a stationary member 20, a latch 21, and a counter-weight lever arm 22 which is pivotally mounted on the rod 11, for reasons hereinbefore set forth.

To each of the receptacles 4 near its upper portion, is connected a pipe 23 having a one-way valve 24 therein. The lower ends of the pipes 23 are connected together by a pipe 25 which is also connected to a cylinder 26 that is supported by the receptacle 4 of the unit 2. A piston 27 is operatively disposed

in the cylinder 26 and is connected, through an operating rod 28, to the toggle mechanism 9 of the unit 2, substantially as shown and for reasons hereinafter set forth. Near the upper portion of the cylinder 26 is an opening 29, for reasons which will hereinafter be explained. A spring 30 is disposed within the cylinder 26 to act against the lower side of the piston 27, as indicated in the drawing.

When an abnormal overload occurs upon the circuit which is protected by the circuit interrupter, the coil 18 of the tripping device 17, which is connected to the circuit (not shown), is energized to release the lever 22, and the toggle mechanism 9 to permit the operating rods 7 to move downwardly to disengage the contact members 5 and 6. The excessive rush of current which flows when the contact members 5 and 6 are disengaged generates a gas in the upper portion of the receptacle 4 which acts against the rods 7 to oppose a downward movement of the same. The gas thus formed is conducted through the pipes 23 and the pipe 25 to the lower portion of the cylinder 26 where it assists the accelerating spring 30 to move the piston 27 upwardly and the rod 7 downwardly, as will be readily understood. After the piston 27 has moved upwardly a predetermined distance, under the force exerted by the spring 30 and the gas, the opening 29 allows the gas to escape, and further movement of the piston is retarded by the air that is compressed in the upper portion of cylinder 26.

Since an overload usually occurs upon only one side of a three-phase circuit, the one-way valves 24 are provided to prevent the generated gas from passing into a receptacle in which no gas is generated and thus rendering the device ineffective. As arranged, the gas can flow only out of the receptacles into the cylinder 26.

In order to close the circuit breaker, the operating lever 16 is moved downwardly until the latch 21 engages the lever 22. The operation of the mechanism 9 moves the rod 7 in an upward direction to effect the engagement of the contact members 5 and 6, as will be understood. The operation of the toggle mechanism 9 also compresses the spring 30 in the cylinder 26 so that the device is again ready to operate in the manner hereinbefore described.

While I have described my invention with respect to a specific structure, it is obvious that modifications may be made within the spirit of the invention, and I desire to include all such modifications within the scope of the appended claims.

I claim as my invention:

1. In a circuit interrupter, the combination with coöperating contact members and an operating mechanism, of a fluid-actuated accelerating device operatively connected to the operating mechanism, and conduits for conducting the gases generated by the separation of the contact members to the accelerating device.
  2. In a circuit interrupter, the combination with coöperating contact members and an operating mechanism, of a fluid-actuated accelerating device operatively connected to the operating mechanism, and conduits having one-way valves therein for conducting the gases generated by the separation of the contact members to the accelerating device.
  3. In a circuit interrupter, the combination with coöperating contact members, and an operating mechanism, of an accelerating device, means for operatively connecting said accelerating device to the said operating mechanism, and means for supplying said accelerating device with gas generated by the separation of the contact members.
  4. In a circuit interrupter, the combination with a substantially air-tight receptacle, coöperating contact members therein, and an operating mechanism therefor, of a fluid-actuated device operatively connected to the operating mechanism, and means for supplying the said device with the gases generated by the separation of the contact members.
  5. In a circuit interrupter, the combination with a substantially air-tight receptacle, coöperating contact members therein, and an operating mechanism therefor, of a cyl-

inder having a piston operatively connected to the operating mechanism, and means for conducting the gas generated in the substantially air-tight receptacle by the separation of the contact members to the said cylinder. 45

6. In a circuit interrupter, the combination with a plurality of substantially airtight receptacles, cooperating contact members therein, and an operating mechanism therefor, of a cylinder having a piston operatively connected to the operating mechanism, and means for supplying the said cylinder with the gas generated in the said receptacles by the separation of the contact members.

7. In a circuit interrupter, the combination with a plurality of substantially airtight receptacles, cooperating contact members therein, and an operating mechanism therefor, of a cylinder having a piston operatively connected to the operating mechanism, means for conducting the gas generated in each receptacle to the said cylinder, and means for preventing the said gases from flowing from one receptacle to another. 60 65

8. In a circuit interrupter, the combination with a plurality of substantially airtight receptacles, co-operating contact members therein, and an operating mechanism therefor, of a cylinder having a piston operatively connected to the operating mechanism, a resilient member for assisting in the operating of the said piston, means for conducting the gas generated in the receptacles to the said cylinder, and check valves to prevent the gas from flowing from one receptacle to another. 70
